(57) **CLAIM**

I claim the ornamental design for the architectural panel with surface texture, as shown and described.

DESCRIPTION

FIG. 1 is a front view of an architectural panel with surface texture, showing my new design.

FIG. 2 is a close-up perspective view of the architectural panel with surface texture.

FIG. 3 is a front view of the architectural panel with surface texture.

FIG. 4 is a left side view of the architectural panel with surface texture.

FIG. 5 is a right side view of the architectural panel with surface texture.

FIG. 6 is a top view of the architectural panel with surface texture.

FIG. 7 is a bottom view of the architectural panel with surface texture.

FIG. 8 is an enlarged bottom view shown along line 8-8 in FIG. 7; and,

FIG. 9 is a further enlarged bottom view shown along line 9-9 in FIG. 8.

The broken lines showing environment in the drawings are included for illustrative purposes only and form no part of the claimed design. The outer broken line boundaries in the figures depicting the boundaries of the claimed design indicate that a specific length, width, and shape form no part of the claimed design and are for illustrative purposes only.
